UNITED STATES PATENT OFFICE.

JOHN ROSS, OF WESSINGTON, SOUTH DAKOTA.

SASH-LOCK.

SPECIFICATION forming part of Letters Patent No. 739,109, dated September 15, 1903.

Application filed January 25, 1902. Serial No. 91,215. (No model.)

To all whom it may concern:

Be it known that I, JOHN ROSS, a citizen of the United States, residing at Wessington, in the county of Beadle and State of South Dakota, have invented certain new and useful Improvements in Sash-Locks, of which the following is a specification, reference being had therein to the accompanying drawings.

My invention relates to new and useful improvements in sash-locks; and its object is to provide a device of this character formed in a single piece of material and adapted to lock the sash to which it is secured and prevent it from being raised from the outside. The device also serves to hold the sash when raised to a desired point and can be utilized as a lift when raising or lowering the window.

With these and other objects in view the invention consists in the novel construction and combination of parts hereinafter more fully described and claimed, and illustrated in the accompanying drawings, showing the preferred form of my invention, and in which—

Figure 1 is an elevation showing a sash locked in lowered position by my improved lock. Fig. 2 is a similar view showing the sash held in raised position thereby, and Fig. 3 is a detail view of the lock detached.

Referring to the figures by numerals of reference, 1 is a window-casing, to the inner surface of each side of which is secured a rack 2, the teeth thereof having their upper edges horizontal. Each rack terminates at a point removed from the sill 3 and forms an angular shoulder adapted to be engaged by the lock when the sash is in its lowest position.

Secured to each side of the sash 4 is a lock 40 formed in a single piece of spring metal. This lock comprises a plate 5; a spring-arm 6, integral therewith and extending therefrom; a head 7, and a lift 8, adjacent to the head. The plate 5 is provided with a desired number 45 of apertures 9 for the reception of fastening means whereby the lock may be secured to the sash. This plate is secured in such a position as to hold the head 7 normally pressed

into contact with the rack 2 by the arm 6. The lifts 8 extend inward from the heads 7 and are preferably arranged substantially under the plate 5, as shown. It will thus be seen that when the fingers are inserted under the lifts and moved upward the heads 7 will be swung back out of engagement with the racks until arms 6 contact with stops 10, arranged upon the sash. The sash can then be raised by continuing to press upward upon the lifts. The upper and lower working faces of the heads 7 are so shaped that one can engage the lower end of the rack and prevent upward movement and the other can engage the horizontal face of any one of the teeth of the rack and prevent downward movement. The end of each head is beveled, as shown at 11, whereby when said head has been disengaged from the end of the rack it can easily slip upward over the teeth and when pressed downward will fit snugly upon a tooth and prevent movement.

It will be seen that the device is simple and effective, can be readily placed in position upon a window, and serves the purposes of a lock, lift, and balance.

In the foregoing description I have shown the preferred form of my invention; but I do not limit myself thereto, as I am aware that modifications may be made therein without departing from the spirit or sacrificing the advantages thereof, and I therefore reserve the right to make such changes as fairly fall within the scope of my invention.

Having thus fully described my invention, what I therefore claim as new, and desire to secure by Letters Patent, is—

In a sash-lock, the combination with a window-frame having a rack-bar secured thereto, of a curved spring-arm having its upper end secured to the lower sash of said frame, the lower end of the arm being provided with a catch and a curved finger arranged on opposite sides thereof, the upper surface of the catch being adapted to springably engage the terminal lower end of the rack-bar to lock the sash against upward movement, the catch also having a spring movement upwardly

over the teeth of the rack-bar so that the under surface of the same will engage any one of the teeth thereby to hold the sash in a raised position, the curved finger serving to operate the catch, and a stop for regulating the movement of said spring-arm, substantially as specified.

In testimony whereof I affix my signature in presence of two witnesses.

JOHN ROSS.
